UNITED STATES PATENT OFFICE.

WILLIS W. CASE, SR., OF DENVER, COLORADO.

BURNER.

1,003,873.

Specification of Letters Patent. Patented Sept. 19, 1911.

Application filed March 3, 1911. Serial No. 612,133.

To all whom it may concern:

Be it known that I, WILLIS W. CASE, Sr., a citizen of the United States, residing at Denver, in the county of Denver and State 5 of Colorado, have invented certain new and useful Improvements in Burners; and I do hereby declare the following to be a full, clear, and exact description of the invention, such as will enable others skilled in the art 10 to which it appertains to make and use the same.

This invention relates to oil burners for general uses, and has for its purpose to provide a burner which will be more simple in 15 construction, effective in action, and less expensive to manufacture than those heretofore proposed.

To these ends the invention consists in the novel details of construction and combinations of parts more fully disclosed hereinafter, and particularly pointed out in the 20 claims.

Referring to the accompanying drawings forming a part of this specification in which 25 like numerals designate like parts in all the views—Figure 1 is a side elevational view of a burner made in accordance with my invention; Fig. 2 is a top plan view partly in section of the parts shown in Fig. 1; Fig. 3 is an end elevational view of the parts shown in Fig. 1 with a slightly modified 30 form of foraminous plate; Fig. 4 is a longitudinal sectional view of the burner; Fig. 5 is an end elevational view partly in section of the burner but looking in a direction opposite to that from which the parts shown 35 in Fig. 3 are seen; Fig. 6 is an enlarged detail view partly in section of the air retarding plates taken on the line 6—6 of Fig. 4 showing an arrangement of perforations slightly differing from that disclosed 40 in Fig. 3; Fig. 7 is an enlarged detail sectional view of a form of the plates slightly differing from that shown in Fig. 2 and 45 removed from the burner; and Figs. 8, 9 and 10 are detail views of still further modified forms of air retarding plates.

1 represents any suitable body portion, but 50 preferably of metal, which is provided with an enlarged air passage 2, and an oil passage 3. Passing through the bottom of the oil passage 3 is a hollow sleeve 4 provided with 55 an oval V-shaped port 5 for the admission of oil into the passage 6 of the sleeve 4, and 7 represents a blunt pointed rod fitting the

sleeve 4, as illustrated, and surrounded by the stuffing box 8 in order to prevent leakage of oil. The extreme end 9 of the rod 7 traverses the passage 6 beneath the V-shaped opening 5, and as will be clear from Fig. 2 60 of the drawings, enables a very fine regulation of the amount of oil admitted to the passage 6. Any suitable means 10 may be provided for turning the rod 7 upon its screw threads 11, and thereby adjusting the 65 end 9 of said rod relatively to the opening 5, as will be readily understood.

The air passage 2 is connected with the delivery 13 of the burner, through the foraminous retarding plates 14 and 15 preferably provided with the registering openings 16, 17 and 18 as shown. These plates may be readily rotated relatively to each other, so as to partially or entirely close the said 70 openings 16 and 17 when desired, as will be 75 more fully described below, and thereby regulate the quantity as well as the pressure of the air delivered through the mouth 13 of the burner. The extreme end of the sleeve or tube 4 is preferably provided with a series 80 of radially projecting fingers 20, as best shown in Fig. 2, and these fingers are located substantially in the center of the larger openings 18 of the retarding plates 14 and 15, for a purpose more fully disclosed here- 85 inafters.

Suitably mounted in the casing 1 is a rod such as 21 having an eccentric finger 22, which engages a slot 23 in one of the plates such as 15, so that when said rod 21 is rotated on its longitudinal axis, the said finger 22 will cause the plate 15 to turn upon an axis passing through its center and the tube 4, and thereby partially or entirely cause its perforations 16 and 17 to move out of register with the corresponding perforations in its companion plate 14. In order that the rod 21 may be turned just far enough to make the registering passages 16 and 17 of the desired size, it is provided at its end 90 100 opposite the finger 22 with an index 25, passing over a suitable scale 26 which conveniently may be placed upon a piece of sheet metal 27 bent upon itself and slotted as at 28 to embrace the extreme reduced end 105 of the said rod 21, as shown. Since these plates 27 possess a certain amount of resiliency when fastened to the casing 1 as by the screw 30, they serve to hold the rod 21 and index 25 in place. The said plate 27 may 110

be also conveniently provided with a turned up stop 31 to limit the extreme movement of the index finger 25.

The operation of my improved burner is as follows:—Oil may be admitted under the action of gravity through the opening 3, whereupon it enters the passage 6 of the sleeve or pipe 4 through the V-shaped opening 5 controlled by the extreme end 9 of the rod 7, and it finds its way to the radially extending fingers 20 of the said pipe 4, and owing to its surface-tension it tends to stick to said fingers. Air may be admitted from any suitable source through the passage 2, whereupon it blows through the central tapered opening 18 of the retarding plates between the said fingers 20, and across the end of said passage 6 and thereupon finely divides or atomizes the oil delivered from the said pipe 4. This finely divided air and oil forms a cone which leaves the burner through its mouth 13 and may be ignited inside the furnace or other place at which it may be desired for use. The amount of oil in the cone may be regulated to a nicety by simply adjusting the extreme end 9 of the rod 7 relatively to the V-shaped opening 5, and by this means the amount of heat delivered by the ignited cone is likewise adjusted to any desired degree.

In order that a more perfect combustion may be attained, and also in order that the cone may be ignited at a point very close to the mouth 13, the index 25 is so turned as to admit air through the registering orifices 16 and 17 of the retarding plates 14 and 15. Since the air under pressure in passing through these cone tapered orifices 16 and 17 is greatly reduced in its velocity, it may enter the cone as almost still air, and thereupon admix with the oil and air entering through the orifices 18 almost to the mouth of the burner, which of course will cause the flame to extend up very close to said mouth, as above stated, while at the same time furnishing sufficient oxygen to insure a very efficient combustion. Of course by turning the index 25 further so as to admit more air through the orifices 16 and 17, the cone becomes longer, and also by changing the position of the extreme end 9 of the rod 7, the said cone may be caused to deliver a greater or less quantity of heat. Further, by changing the degree of the registration of the openings 16 and 17, the oxidizing or reducing portion of the flame may be brought to any desired point of the material being heated. This feature, among others, renders my burner exceedingly useful for metallurgical operations.

I find from actual tests that an exceedingly efficient metallurgical burner can be produced by the means above disclosed when air at only about four ounces pressure is admitted into the passage 2. I have further

found that by simply converging the orifices 16 and 17 as illustrated in Fig. 7, the cone can be made to converge at any particular point in the furnace, and thereby an intense heat may be delivered wherever desired. After converging, of course, said cone then diverges as it traverses the furnace.

In the modification shown in Fig. 8, a single sheet 35 of foraminous material is disclosed. I find for certain purposes that such a sheet, or even wire cloth, may be used instead of the retarding plates 14 and 15.

In the further modifications disclosed in Figs. 9 and 10, I have illustrated retarding disks 36 and 37 provided with radial openings 38 adapted to be placed into registering or non-registering position and by a means similar to that disclosed in connection with the retarding disks 14 and 15. I have found for certain purposes that these disks 36 and 37 give excellent results. In all cases, however, it will be observed that I may use a gravity feed for the oil and that a simple fan blower producing a pressure as low as from four to six ounces or less gives most excellent results.

It is obvious that those skilled in the art may vary the details of construction and the arrangement of parts without departing from the spirit of my invention, and therefore I do not wish to be limited to such features except as may be required by the claims.

What I claim is:

1. In an oil burner, the combination of means for supplying oil; a valve controlling said means; means comprising a plurality of radially extending fingers for subdividing said oil after it passes said valve; means for admitting air under pressure past said subdividing means and thereby atomizing said oil and forming a fuel cone; and means comprising a foraminous plate for discharging additional air under a less pressure than said first mentioned air into said cone, substantially as described.

2. In an oil burner, the combination with a casing provided with oil and air passages, of a pipe passing through said oil passage provided with an orifice; a rod located in said pipe adapted to control said orifice; means at one end of said pipe adapted to subdivide any oil that may pass said orifice; and a plate having a central opening coacting with said subdividing means adapted to permit air under pressure from said air passage to blow past said subdividing means and thereupon further subdivide said oil, substantially as described.

3. In an oil burner, the combination with a casing provided with oil and air passages of a pipe passing through said oil passage provided with a V-shaped orifice; a rod located in said pipe, the end of which is adapted to control said orifice; means com-

- prising radially extending fingers at one end of said pipe adapted to subdivide any oil that may pass said orifice; and a foraminous plate having a central opening co-acting with said subdividing means adapted to permit air under pressure from said air passage to blow past said subdividing means and thereupon further subdivide said oil, substantially as described.
10. 4. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; and a plurality of foraminous air retarding plates having registering orifices coacting with said fingers, substantially as described.
15. 5. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; a plurality of foraminous air retarding plates having registering orifices coacting with said fingers; a rod carried by said casing having a reduced end; an index on said end; a bent plate provided with a scale holding said rod in place; and a connection between said rod and one of said plates adapted to cause said orifices to move relatively to each other, substantially as described.
20. 6. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; a plurality of foraminous air retarding plates having registering orifices coacting with said fingers; and means for causing said orifices to register or non-register at will, substantially as described.
25. 7. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; a plurality of foraminous air retarding plates having registering orifices coacting with said fingers; a rod carried by said casing having a reduced end; an index on said end; a bent plate provided with a scale holding said rod in place; and a connection between said rod and one of said plates adapted to cause said orifices to move relatively to each other, substantially as described.
30. 8. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; a plurality of foraminous air retarding plates having registering orifices coacting with said fingers; and means for causing said orifices to register or non-register at will, substantially as described.
35. 9. In an oil burner, the combination with a casing provided with oil and air passages of a pipe provided with a V-shaped opening passing through said oil passage; a rod having a blunt end located in said pipe and controlling said opening; a plurality of oil dividing fingers associated with said pipe; a plurality of foraminous air retarding plates having registering orifices coacting with said fingers; and means for causing said orifices to register or non-register at will, substantially as described.

In testimony whereof, I affix my signature, in presence of two witnesses,

WILLIS W. CASE, Sr.
